UNITED STATES PATENT OFFICE

1,999,294

BOOK COVER CEMENTING MACHINE

Arthur S. Johnson, Beverly, Mass., assignor to
 United Shoe Machinery Corporation, Paterson,
 N. J., a corporation of New Jersey

Application September 8, 1931, Serial No. 561,636

10 Claims. (Cl. 91—50)

This invention relates to cementing machines and is illustrated as embodied in a machine, particularly adapted for applying cement to book covers, of the type shown in Letters Patent of the United States, No. 1,849,540, granted March 15, 1932, upon an application filed in the name of John W. Cosgrove, deceased.

Before their application to the books, book covers are commonly made up as "cases" comprising the cover material and filler pieces, or stiffeners. The cover material is cut larger than the filler pieces and, after cement has been applied to the margins of the fillers and to the projecting margins of the covers, the edges of the cover material are folded over the filler pieces. The problem of applying cement simultaneously to work pieces which comprise portions of different thicknesses is satisfactorily accomplished by machines of the type illustrated in the Cosgrove application in which separate applying rolls are utilized for coating the margins of the filler and the cover and in which separately driven individually yieldable presser or work supporting rolls are provided to coat with the respective applying rolls. In the arrangement there shown, one applying roll wide enough to cover both margins is brought into contact with the filler piece, and a second or auxiliary roll, receiving cement from the first roll, is brought into contact with the margin of the cover.

Because of the fact that book covers are not uniform in the margin of the projecting cover material, it is essential that provision be made for adjustment of the second or auxiliary roll with respect to the primary coating roll. One important feature of the present invention resides in an improved mounting for an auxiliary roll in a machine of the type referred to, permitting adjustment not only axially of the roll to accommodate book covers having different widths of projecting margins of cover material, but also to provide for adjustment toward and away from the work of this auxiliary roll, thereby to bring the auxiliary roll into contact with the cover irrespective of its thickness. Still another adjustment in the illustrated machine provides for relative movement of the auxiliary and primary coating rolls to vary the distance between said rolls and hence the quantity of cement transferred. This allows the quantity of cement supplied to the auxiliary roll to be kept uniform in all positions of adjustment and the two rolls to be brought into line contact at the desired separation. The drive for the illustrat-

ed auxiliary roll embodies a universal joint and thus permits the driving of said roll without binding and at a uniform speed in all of said positions of adjustment, avoiding any wrinkling or stretching of the cover material such as would result from differences in the speeds of the two coating rolls.

Still other features of the invention reside in an improved gage mechanism comprising a gage fence overhanging a portion of the work and coacting with a characteristic feature of the work spaced from the edge thereof, as for example the edge of the filler piece.

These and other features of the invention will be best understood from a consideration of the following specification taken in connection with the accompanying drawings, in which

Fig. 1 is a front elevation of the machine;

Fig. 2 is a detail view partly in section of the mounting for the doctor roll;

Fig. 3 is a perspective view of a book cover which has been coated;

Fig. 4 is an enlarged detail in perspective of the mounting for the doctor roll;

Fig. 5 is a side elevation with portions broken away to show the arrangement for driving the various rolls;

Fig. 6 is an enlarged view in perspective of the applying and presser rolls; and

Fig. 7 is a vertical section showing the mounting for the transfer roll and for one of the presser rolls.

The arrangement of the machine, comprising as it does a primary coating roll 10, an auxiliary coating roll 12, and the coacting presser rolls 14 and 16, adapts it particularly for coating pieces of work such as that shown in Fig. 3. This comprises a piece of thin cover material C and two pieces of thicker filler material F, superposed on the cover material and spaced from the edges thereof. The primary coating roll 10 is wide enough to extend over the margin A of the cover C and to coat the margins B of the filler pieces F. The coacting presser roll 14 is adjusted to a position such that it will accommodate the combined thicknesses of the cover C and a filler piece F so as thereby to hold the margin B in firm contact with the applying roll 10. On the other hand, the auxiliary coating roll 12 which receives its coating material from that portion of the primary coating roll 10 which is above the margin A, and hence not needed on that roll, and itself applies the coating to the margin A extending from the outer edge thereof close up to the edge of the filler piece. The corresponding presser roll

16 grips the thin cover C between itself and the auxiliary roll 12.

Coating material is supplied to the primary roll 10 from a pick-up roll 18 dipping in a trough 28 which is supplied with cement at a uniform level by means of a barometric inverted supply can 22. The quantity of material taken out of the receptacle 20 by the pick-up roll 18 is controlled by a driven doctor roll 24 and the material carried over the upper surface of the pick-up roll 10 is delivered to a transfer roll 26 which in turn delivers it to the coating roll 10.

All of the rolls which handle coating material are driven in the same direction as indicated by the arrows in Fig. 1. To this end the coating roll 10 is mounted on a shaft 30 journaled in the frame 32 of the machine and driven by suitable gear connections within the casings 34 and 36 from a source of power such as an electric motor 38. The direction of rotation of the various rolls is indicated by arrows in Fig. 1 and suitable gear connections are provided for rotating these rolls in the directions indicated so that the peripheral speeds of adjacent rolls are equal. In order that those rolls which are adjustable may be driven in any position of adjustment without binding, the shafts connecting the adjustable rolls with the gears in the gear case 36 are provided with universal joints 40. This is true of the doctor roll 24, the transfer roll 26, the auxiliary roll 12, and the presser rolls 14 and 16. By this arrangement the pitch relation of driving gears is unchanged by adjustment of the rolls and hence their speed is held at its predetermined desired value.

The reason for providing universal joints in the shaft of the transfer roll 26 lies in the peculiar mounting provided for this roll. In order to avoid extraordinary care and expense in drilling the frame to receive the shafts of the rolls 10, 18 and 26 so that the periphery of the transfer roll 26 will make substantially a line contact with each of the adjacent rolls 10 and 18 at a separation of only a few thousandths of an inch, provision is made for adjusting the roll 26 to take care of any slight variations resulting from imperfect drilling of the frame or machining of the rolls. Accordingly, the roll 26 is journaled in a hanger 42 shaped like a bell crank and pivoted upon a stud 43. The other arm of the bell crank is slotted to receive a clamping bolt 46 and to permit adjustment in a direction substantially normal to the line connecting the centers of the rolls 10 and 18. The diameter of this transfer roll 26 is greater than the shortest distance between the peripheries of the rolls 10 and 18 and it can, therefore, be brought into just the desired relation to said rolls.

Control of the quantity of material delivered by the pick-up roll 18 is facilitated by journaling the doctor roll 24 in a sliding block 50 (Figs. 2 and 4) which is received within a slideway provided in the frame, providing thus for maintenance of the axes of the rolls 24 and 18 in parallelism. The position of the doctor roll 24 may be adjusted by means of a micrometer screw 52 which has a shank 54 threaded in the frame as shown in Fig. 4. This screw has a flange 56 engaging a groove between the block 50 and a cover plate 58 so that turning the screw causes the block 50 to be adjusted in and out to carry the doctor roll toward or away from the pick-up roll 18. A scraper 60 is provided on the block 50 for contact with the up-going side of the doctor roll 24 so as to keep said roll clean and insure its perfect control of the quantity of material on the

larger roll 18. The retention of the adjusted position of screw 52 is assured by a spring-pressed ratchet pin 62. A stop screw 64 (Fig. 2) is threaded in the block 50 and locked in position 5 so as thereby to prevent the doctor roll 24 from being forced into contact with the roll 18 in such a manner as to injure said rolls.

In the presentation of book covers to the coating rolls 12 and 14 arranged in series, they are laid upon a work table 70 mounted upon an adjustable bracket 72 held upon the machine by means of the hand screw 74. On this bracket there is also mounted for in-and-out adjustment a fence bracket 76 (Fig. 5) carrying a gage fence 78. This gage fence overhangs the margin A of the cover and is arranged to coact with the edges of the filler pieces F which are spaced from the outer edge of the book cover but which, by being thicker and more rigid, provide a better gaging surface than does the edge of the cover C which usually is flexible. The screw and slot mounting 80 (Fig. 1) provided for supporting the fence in adjusted position upon the bracket 76 allows the lower edge of the gage fence 78 to be brought close to the upper surface of the cover without contacting therewith and at such a height that the gage fence 78 will contact with the edges of the fillers F. By in-and-out adjustment of the fence bracket 76 it is possible to adjust the position of the gage fence 78 with respect to the edge of the cover C so as thereby to accommodate different widths of the marginal portions A.

Successful coating and feeding of the work depends to a substantial extent upon the proper positioning of the presser rolls 14 and 16. Accordingly, the frame 32 has attached to its front face a hollow block 82 which receives blocks 84 (Fig. 6) and 86 (Fig. 7) in which are journaled the presser rolls 16 and 14 respectively. A slotted cover plate 88 retains these blocks within the hollow block 82 and permits vertical adjustment of the presser rolls with the assurance that the axes of said rolls will be kept in perfect parallelism with the corresponding coating rolls 12 and 10. The positions of these blocks are determined by similar mechanisms one of which is shown in section in Fig. 7 and comprising in each instance a screw 90 which is held fixed in the block 86 by means of a pin 92. Surrounding this screw is a spring 94 which presses against the under side of the block 86 to hold the presser roll resiliently against the work. The degree of pressure provided by this spring is determined by means of a sleeve 96 abutting the spring 94 and threaded in the hollow block 82 and held in adjusted position by a set screw 98. This sleeve 96 is provided with a knurled head 100 to facilitate its adjustment. In order to limit the upward movement of the slideable block 86 the bolt 90 is provided with a stop nut 102 held in adjusted position by a lock nut 104. It will be seen that the arrangement just described provides for independent adjustment of the limiting position of the presser roll and the spring tension with which the presser roll is held against the work. A like mechanism is provided for the block 84. It will be seen from Fig. 6 that the block 84 is provided with a dovetail 106 upon which the table bracket 72 is secured. As a result the position of the upper surface of the table always corresponds exactly with the position of the upper surface of the presser roll 16.

Assuming that the coacting applying and feeding rolls 10 and 14 are in correct relation to grip

the margin of the filler piece F, it then becomes necessary to adjust the position of the auxiliary roll 12 to coat the margin A of the thin cover stock C. To permit this adjustment, the mounting of the roll 12 comprises a vertical plate 110 having a rib and groove connection 112 (Fig. 1) with the frame 32. The back of this plate is slotted to receive the flange 114 upon an adjusting screw 116 which is threaded in the frame 10 thereby facilitating the vertical adjustment of the auxiliary roll 12 so that it may be brought into good contacting relation with the cover stock C. After the plate 110 has been adjusted it may be clamped in adjusted position by means 15 of a screw 118 passing through a slot in the plate into the frame. The lower portion of the front face of the plate 110 has an outwardly projecting rib 120 and coacting with this rib to support the roll is an angle block 122 which is secured to the plate 110 by means of a bolt 124 passing through 20 a slot in said angle block (Fig. 6). This slot is horizontal, in line with the top and bottom faces of the rib 120, and permits an axial adjustment of the auxiliary roll 12 across the face of the primary roll 10 to cause the auxiliary roll to coat the 25 whole of margin A and to be positioned close to the edge of a filler piece F. It will be seen that the vertical adjustment of the auxiliary roll may have destroyed the spacing between that roll and the primary roll 10 and thus changed the quantity 30 of coating material which is removed by the auxiliary roll and applied to the work. To restore the correct relation between these two rolls, a bearing block 130 for the auxiliary roll 12 is dovetailed in the lower face of the angle block 122 thereby to permit adjustment of this block 130 in a horizontal direction toward and away from the primary roll 10. A tight fit of 35 this bearing block 130 in the angle block 122 is insured by a gib 131 pressed into position by means of locked screws 132. To facilitate the easy adjustment of the bearing block exactly to the desired position, a thumb screw 134 is provided which is threaded into said block and 40 which has a ratchet 136 received in a groove 137 (Fig. 1) in the lower face of an overlapping plate 138 attached by screws to the front face of the angle block 122. This plate 138 is also drilled to receive a spring-pressed pin 140 (Fig. 5) which 45 bears against the ratchet 136 thereby to hold the screw 134 in adjusted position. The shaft for the auxiliary roll 12 is provided with universal joints 49 as noted previously so that it may be driven evenly and at the same speed in any position of adjustment. If the auxiliary roll 12 moved faster than the primary roll 10, the application of cement would not be uniform and the work would tend to wrinkle between the two.

It will be seen, therefore, that in the use of the machine the operator is enabled to control the application of cement to the margins A and B of the assembled cover and to cause it to be fed through the machine without rumpling or doubling. Assuming that he is starting the machine for the first time on any particular lot of covers, he may find it necessary to adjust the nuts 102 on the supports 84 and 86 for the presser rolls 14 and 16 so as thereby to control the limiting positions of said rolls to prevent contact with the coating rolls. Preferably the rolls 14 and 16 will be positioned at the same level to prevent distortion of the work. He may need also to adjust the tension of the springs 94 by means of which these rolls are held against the work and this can be done by turning the sleeves 96 by their heads

100 and it will be independent of the adjustment of the limiting position of these rolls. Adjustment of the auxiliary roll 12 across the face of the primary roll to accommodate a particular width of margin A will be effected by loosening the screw 124. He also may have to adjust the auxiliary roll 12 up and down by turning the screw 116 to cause it to coat properly with the thin cover stock C and then he will adjust it by means of the screw 134 to cause just the correct 10 amount of coating material to be applied and to get line contact with the roll 16. The work supporting table 78 which is carried by the block 24 for the presser roll 16 will be at the correct height but it may be necessary to adjust the gage fence 15 78 in accordance with the width of the margin A of the particular piece of work by loosening the screw 76 and also in accordance with the thickness of the cover stock C by loosening the screws in the slots 89. These adjustments made, he will 20 control the quantity of latex delivered by the pick-up roll 18, by turning the screw 52 to adjust the doctor roll 24 and, guiding the work by means of the gage fence, will cause the coating rolls 16 and 12 operating in series to coat the 25 margin B of the filler stock and the margin A of the cover stock, to the end that later the margin A may be folded over on the margin B to provide a finished cover ready for application to a 30 book.

Having thus described my invention, what I claim as new and desire to secure by Letters Patent of the United States is:

1. In a coating machine, at least two coating rolls arranged in series relation to operate upon the same side of the work, means for supplying a coating substance to one of said rolls and thence to another roll, one of said rolls being mounted for adjustment across the face of the other roll to vary its relation to the margin of the work 40 to be coated, means for driving said rolls at the same peripheral speed, and means for varying the distance between the axes of said rolls to control the quantity of material transferred therebetween and without varying the speed of 45 rotation of either roll.

2. In a coating machine, a pair of coating rolls arranged to operate successively upon the same side of the work, means for supplying a coating substance to one of the rolls, the second roll receiving coating substance from the first roll, a 50 slidably mounted bearing for the second roll, guiding means for said bearing permitting movement of the second roll toward and away from the other roll in a direction substantially normal to the axis of the first roll thereby to control the transfer of coating material between the rolls, and means for driving said slidably mounted roll at the same speed in all positions of adjustment.

3. In a coating machine, a pair of coating rolls arranged to operate successively upon the same side of the work, means for supplying a coating substance to one of the rolls, the second roll receiving coating substance from the first roll, a 65 slidably mounted bearing for the second roll, means for adjusting said bearing to move the second roll toward and away from the other roll thereby to control the transfer of coating material between the rolls, means for adjusting said bearing to move the second roll axially across the face of the first roll thereby to vary its relation to the margin of the work to be coated, and means for driving said slidably mounted roll at the same speed in all positions of adjustment. 70 75

4. In a coating machine, coating coating and presser rolls adapted to grip the work, means for driving one of said rolls to feed the work, a table for supporting the work for delivery to said rolls, and a gage fence on said table overhanging a portion of the work and coacting with a characteristic feature of the work spaced from the edge thereof to gage the work thereby. 5
5. In a machine for coating book covers provided with superposed filler pieces spaced from an edge thereof, coating coating and presser rolls for gripping and feeding the work, a table for supporting said work, and a gage fence mounted on said table to overhang a margin of the covers and to coact with an edge of the filler pieces. 10
6. In a machine for coating book covers provided with superposed filler pieces spaced from an edge thereof, coating coating and presser rolls for gripping and feeding the work, a table for supporting said work, and a gage fence mounted on said table to overhang a margin of the cover and to coact with the edge of the filler piece, said gage fence being adjustably mounted for movement toward and away from said table to compensate for different thicknesses of covers. 15
7. In a machine for coating book covers provided with superposed filler pieces spaced from an edge thereof, coating coating and presser rolls for gripping and feeding the work, a table for supporting said work, and a gage fence mounted on said table to overhang a margin of the cover and to coact with an edge of the filler piece, said gage fence being adjustably mounted transversely of said table to coact with filler pieces which are spaced differently from the edges of the covers. 20
8. In a machine for coating book covers pro- 25
- vided with superposed filler pieces spaced from an edge thereof, coating coating and presser rolls for gripping and feeding the work, a table for supporting said work, a gage fence mounted on said table to overhang a margin of the cover and to coact with an edge of the filler piece, and means for adjustably supporting said gage fence to permit adjustment in a direction transversely of the margin of the cover and toward and away from said table. 30
9. In a coating machine, a work support, a plurality of coating rolls arranged to operate in series upon the same side of a piece of work on said support, means for supplying coating material to one roll and from it to the second roll, means for driving said rolls at the same peripheral speed, a bearing for the second of said rolls movably mounted for adjustment toward and away from the work support, said bearing being also mounted for adjustment substantially parallel to the work support toward and away from the first roll, whereby the transfer of coating material between the rolls may be kept the same, and driving means including connections for said second roll unaffected by said adjustments. 35
10. In a coating machine, a work support, a plurality of coating rolls arranged to operate in series upon the same side of a piece of work on said support, means for supplying coating material to one roll and from it to the second roll, means for driving said rolls at the same peripheral speed, and a bearing for the second of said rolls movably mounted for adjustment toward and away from the work support and also mounted for adjustment axially across the work area to be coated. 40

ARTHUR S. JOHNSON.
